Patented Nov. 16, 1976

242,337

COUNTERWEIGHT FOR A LIFT TRUCK

Donald J. De Priester and Darrell C. Fuller, Niles, and
Jack E. Loomis, Kalamazoo, Mich., assignors to Clark
Equipment Company, Buchanan, Mich.

Filed Nov. 27, 1974, Ser. No. 527,788

Term of patent 14 years

Int. Cl. D12—05

U.S. Cl. D12—60

Published under the second Trial Voluntary Protest
Program on Sept. 16, 1975, as document No. B823,492

FIG. 1

FIG. 2

FIG. 3

FIG. 4

FIG. 5

FIG. 6

FIG. 1 is a perspective view of a counterweight for a lift truck showing our new design;

FIG. 2 is a right side elevational view thereof;

FIG. 3 is a front perspective view of a counterweight for a lift truck showing a second embodiment of our new design, the sole difference being in the addition of the grillwork as illustrated;

FIG. 4 is a right side elevational view of FIG. 3;

FIG. 5 is a top plan view of FIG. 3; and

FIG. 6 is a rear perspective view of FIG. 3.

The portions shown in broken lines in FIG. 1 are for illustrative purposes only.

We claim:

The ornamental design for a counterweight for a lift truck, as shown and described.
